UNITED STATES PATENT OFFICE.

JOEL HERBERT SHEDD, OF PROVIDENCE, RHODE ISLAND, ASSIGNOR TO
WALTER C. CARR, OF NEW YORK, N. Y.

HYDRAULIC AIR-COMPRESSOR.

SPECIFICATION forming part of Letters Patent No. 738,576, dated September 8, 1903.

Application filed December 9, 1902. Serial No. 134,470. (No model.)

To all whom it may concern:

Be it known that I, JOEL HERBERT SHEDD, of the city of Providence, county of Providence, and State of Rhode Island, have invented certain new and useful Improvements 5 in Hydraulic Air-Compressors, of which the following is a specification.

My invention relates to hydraulic air-compressors of the type illustrated in Letters 10 Patent No. 543,411, dated July 23, 1895, and granted to Charles H. Taylor, and more particularly to an air-compressor in which a series of horizontal air-bars of an inverted-V shape in cross-section and communicating at 15 each end with a submerged air-chamber are used for entraining the air in the head of the descending column of water, as illustrated in Letters Patent No. 704,059, dated July 8, 1902, and granted to William J. Linton.

20 The object of my invention is to render these air-bars more efficient; and this object I accomplish in the manner and by the means hereinafter fully described in connection with the accompanying drawings, in which—

25 Figure 1 is a horizontal plan of the parts located in the head-piece of the apparatus for entraining the air; Fig. 2, a vertical section on the line $x-x$ of Fig. 1; Fig. 3, a detail of Fig. 2; Fig. 4, an elevation, and Fig. 5 a bottom plan, of a part of one of the air-bars.

Similar letters of reference refer to corresponding parts throughout the several figures.

In Figs. 1 and 2 there is shown the general arrangement of vertical air-supply pipes A, 35 A', A'', and A'', the submerged air-chamber C, the air-bars B B' B'', &c., and the vertically-adjustable deflector-bars D D' D'', &c., as heretofore employed.

40 My improvement, as shown in Figs. 3, 4, and 5, consists in closing the lower sides of the air-bars except for narrow longitudinal openings which are left, preferably, along each of their two edges. I do this by inserting in the bottom of each air-bar a screen or bottom 45 plate P P', somewhat narrower than the bottom of the air-bar, so as to leave a narrow opening on each side thereof for the passage of the air into the water. These bottom plates may be secured in place by any suitable means, 50 as by gussets g g', bent, as shown, and riveted

at intervals to the edges of the plates and the lower edges of the air-bars. It will be understood, however, that I do not limit myself to this means for closing the bottoms of the air-bars, for it is obvious that the same thing can be 55 accomplished in other ways—as, for instance, by bending over one side of the air-bars, left wider for the purpose, and, if desired, cutting longitudinal openings for the air along the angle thus formed, thus practically converting the air-bars into air-pipes closed to the action of the water flowing through the apparatus except for one or more slits along their lower sides. The effect of this construction is to throttle the air after it enters 60 the air-bars from the air-chamber, and thereby cause its more even distribution throughout the length of the air-bars. Thus every part of the body of flowing water is supplied immediately and within a limited horizontal 65 space with its proper volume of air, and, as the result, the efficiency of the apparatus is greatly increased.

What I claim as new, and desire to secure by Letters Patent, is—

1. In a hydraulic air-compressor, a series 75 of horizontal air-bars communicating at their ends with a submerged air-chamber and means for throttling the air after it enters the air-bars from the air-chamber to secure 80 its more even distribution throughout the length thereof, substantially as described.

2. In a hydraulic air-compressor, a series 85 of horizontal air-bars communicating at their ends with a submerged air-chamber and closed to the action of the water flowing through said compressor except for one or more narrow openings along the lower sides thereof, substantially as described.

3. In a hydraulic air-compressor, a series 90 of horizontal air-bars substantially closed throughout their length except for one or more narrow longitudinal openings along or near their lower sides, substantially as described.

4. In a hydraulic air-compressor, an air-bar substantially closed throughout its length except for one or more narrow longitudinal openings along or near its lower side, substantially as described.

5. In a hydraulic air-compressor, an air-bar and means for throttling the air after it enters each end of said air-bar from an air-chamber, for the purpose specified.
- 5 6. In a hydraulic air-compressor, a series of air-bars which are in the form of an inverted V in cross-section and are closed along their bottoms except for narrow openings on each side thereof.
- 10 7. In a hydraulic air-compressor, an air-

bar, B, and screen or bottom plate, P, substantially as described.

In testimony whereof I have hereunto affixed my signature in presence of two witnesses.

JOEL HERBERT SHEDD.
